F. A. WHITTEN
FRAME CONSTRUCTION

Filed Aug. 15, 1925

Inventor

Frank A. Whitten

By Blackmorg, Spencer & Galt
Attorneys

UNITED STATES PATENT OFFICE.

FRANK A. WHITTEN, OF DETROIT, MICHIGAN, ASSIGNOR TO GENERAL MOTORS CORPORATION, OF DETROIT, MICHIGAN, A CORPORATION OF DELAWARE.

FRAME CONSTRUCTION.

Application filed August 15, 1925. Serial No. 50,435.

The object of the invention is to provide an improved frame construction which will be strong and resist weaving and distortion. In its preferred form my frame embodies channel iron side frame members having down-turned ends and a plate connecting the side frame members, the plate having portions secured to the opposed flanges of the channel irons. The part of the plate connecting the last named portions, and the opposite side of the plate which is inclined to conform to the curvature of the down-turned ends of the side frame members make the plate, in effect, a shallow channel member possessing considerable rigidity.

I have also preferably formed my plate to provide outwardly projecting supports for the body sills of the vehicle. These supports may be of angular shape to provide the requisite strength.

In the drawings:

Fig. 1 is a top plan view with parts broken away showing my improved construction; and

Figure 2 is a side elevation of the construction shown in Figure 1.

The reference character 2 indicates a pair of side frame members having down turned end portions 4 to which the springs are usually secured. The side frame members 2 are of channel iron having their channels inwardly facing and are connected by a plate 6 having portions 8 secured to the lower flanges of the channels and portions 10 secured to the upper flanges of the channels. The connecting portion 12 of the plate is preferably inclined and the ends thereof are preferably cut away as at 15 to clear one of the flanges. The portions 10 of the plate preferably conform to the curvature of the downturned ends 4 of the side frame members. With this construction the plate 6 constitutes, in effect, a shallow channel member thereby supplying the required rigidity.

The plate is shown provided with outwardly projecting parts 14 which serve to support the ends of the customary body sill, indicated at 16. In order that these parts may have the requisite strength the plate is preferably crimped to form what constitutes, in effect, an angle shaped member 17 with which the parts 14 are integral. The plate is preferably secured to the side frame members adjacent the legs of the angle portion

17, as shown at 18 and 20, to prevent spreading of the angle under load.

It is apparent that I have, by this construction, provided a simple rigid frame construction which will resist weaving and one which also preferably embodies sill supporting means thereby eliminating separate brackets or cross members customarily used for this purpose.

I claim:

1. The combination of a pair of channel iron side frame members having the channels thereof opening inwardly, a plate-like member having opposite extending portions secured to the opposite flanges of said channels, said member having the portions between said flanges cut away to clear one of the flanges and extending at an angle thereto.

2. The combination of a pair of side frame members of channel shape having the channels thereof opening toward each other, the extremities of said frame members being downwardly inclined, a plate-like member connecting said frame members and comprising portions adapted to be secured to the lower flanges of the channel irons and portions adapted to be secured to the upper flanges thereof and conforming to the curvature of the down turned portions of the channel irons, and upwardly extending portions connecting the first named portions.

3. The combination of a plurality of side frame members, a plate-like member connecting the side frame members, the plate-like member having a crimped portion, forming an angular ridge in the plate-like member spaced from the side frame members, and extending transversely of the frame and beyond the marginal edges of the plate-like member and the side frame members, to afford a support for a body sill, and means for securing the plate-like member to the side frame members on either side of the ridge.

4. A transverse chassis frame member to connect a pair of longitudinal channel shaped chassis frame members, consisting of a plate-like member having a portion to be secured to the upper flange of a channel member and an oppositely extending portion to be secured to the lower flange of a channel member, and an integral member formed on said upper portion and projecting beyond the margins of the plate-like member to serve as a support for a body sill.

5. The combination of a pair of channel iron side frame members having the channels thereof opening inwardly, a plate-like member having portions secured to the opposite flanges of said channels, said member being cut away between said portions to clear one of the flanges, said plate-like mem-

ber being formed to provide an angled member extending transversely of the frame and having ends projecting outwardly there-¹⁰ beyond, said ends serving as supports for the body sills.

In testimony whereof I affix my signature.
FRANK A. WHITTEN.
